J. L. H. & Co.,

ATTORNEY

UNITED STATES PATENT OFFICE.

ABRAHAM BEBEL, OF BROOKLYN, NEW YORK, ASSIGNOR TO THE DE LONG HOOK AND EYE COMPANY, OF PHILADELPHIA, PENNSYLVANIA, A CORPORATION OF PENNSYLVANIA.

HOOK AND EYE TAPE.

Application filed March 10, 1924. Serial No. 698,010.

This invention relates to hook and eye tape employed as a closing means for securing together the edges of brassières or other garments of wearing apparel and it has for 5 its principal object to provide an improved and novel means for securing the members of hook and eye fasteners to the tape or braid in such manner as to hold the same in flat position thereon.

10 It is also an object of the invention to provide novel means for securing the bill or hook end portions of the hooks to the tape or braid on which they are mounted, so as to hold the same flat against such tape or 15 braid.

For further comprehension of the invention, and of the objects and advantages thereof, reference will be had to the following description and accompanying drawing, and to the appended claim in which the various novel features of the invention are more particularly set forth.

Fig. 1 of the drawing is an outside rear view showing a portion of a brassière having the invention embodied therein;

Fig. 2 is a fragmentary inside rear view;

Fig. 3 is a horizontal sectional view taken on the line 3—3 of Fig. 2; and

Fig. 4 is a detail transverse sectional view taken on the line 4—4 of Fig. 2.

In the drawing, the reference numerals 10 and 10' indicate the meeting marginal portions of the main body material of a brassière or other garment of wearing apparel. To the edges of these portions are attached the respective braids or tapes 12 and 13 of relatively stiff material which carry the hooks and eyes, the braid or tape 12 carrying the hooks 15 and the braid or 40 tape 13 the eyes 16. The braid or tape 12 is secured to the edge portion 10 by means of rows of stitches 11. The braid or tape 13 is secured to the edge portion 10' by means of rows of stitches 11'. The braid or tape 12, 45 which carries the hooks 15, is flush along one edge with the edge of the part 10, while the braid or tape 13 which carries the eyes 16 overlaps or extends beyond the edge of the part 10', the eyes 16 being secured to the 50 braid or tape in such position that all but

their tips will be covered by the part 10'. The hooks and eyes are secured in the usual manner by metal fastening means 16' to the respective braids or tapes 12 and 13, such fastening means including projecting portions which extend through the eyes of the 55 said hooks and eyes and the tapes. When the two edges of the brassière or other garments of wearing apparel are attached together the part 10 overlaps the part 10', as 60 shown, and thereby conceals the hooks and eyes, the hooks being arranged with their beaks lying inward of the edge of the said part 10. Metal clips such as 18 may be placed over the top and bottom of the 65 brassière or other garments of wearing apparel at the meeting edges thereof to cover the ends of the braids or tapes 12 and 13.

For the purpose of holding the hooks flat upon the braid or tape 12 loops are provided at intervals in a row of stitching 19, which loops are in engagement with the hooks at a point intermediate the bill and shank portions thereof forwardly of the hump 15', as shown in Fig. 3 of the drawing. These loops are formed at intervals as the row of stitching progresses and are thrown out, around and underneath the bill portions of the hooks and engage the latter, as indicated at 19^a in Fig. 4 of the drawing. 75 The row of stitching 19 is formed before the braid is placed upon the part 10 of the structure, as shown in the drawing. In the construction as shown, the row of stitching 19 extends along a line substantially tangent 80 to the outer end portions of the row of hooks, as shown in Fig. 2 of the drawing, but the invention is not limited to a construction in which the row of stitching is located in such exact relationship to the 85 hooks.

One of the rows of stitching 11' is engaged with the eyes 16 and serves to hold the latter in flat contact with the braid or tape 13.

Having thus described my invention what 90 I claim as new and desire to protect by Letters Patent of the United States is as follows:

A hook and eye tape structure for closing the edges of garments of wearing apparel 100

comprising a tape, hooks having shank and bill portions, means for securing the rear ends of the shank portions to said tape, a row of stitching extending longitudinally of the said tape and having loops formed at intervals therein, which loops extend laterally toward an edge of the said tape and which are in engagement with the outer end portions of the said hooks at points intermediate the shank and bill portions thereof for holding the same flat against the said tape. In testimony whereof I have affixed my signature.

ABRAHAM BEBEL.
